UNITED STATES PATENT OFFICE.

JACOB GEORGE SCHWARTZ, OF ROCKINGHAM TOWNSHIP, SCOTT COUNTY, IOWA.

BLOTTING INKSTAND.

1,405,558.

Specification of Letters Patent. Patented Feb. 7, 1922.

Application filed July 26, 1920. Serial No. 399,170.

To all whom it may concern:

Be it known that I, JACOB GEORGE SCHWARTZ, a citizen of the United States, residing at Rockingham Township, in the 5 county of Scott and State of Iowa, have invented a new and useful Blotting Inkstand, of which the following is a specification.

My invention relates to improvements in blotting-inkstands, which combine a tape 10 blotting device with an inkstand and a pen rack; and the objects of my invention are to provide an ever ready means of having a clean blotter, a non-spilling inkstand capable of keeping ink unaffected by evaporation 15 and a pen rack all in one device, in such manner as to combine efficiency with an ample supply of fresh material on hand for the use of the clerical.

I attain these objects by the mechanism 20 illustrated in the accompanying drawings, in which:

Figure 1, is an end view of the blotting-inkstand.

Fig. 2, is a plan view thereof.

25 Fig. 3, is a side elevation of the ink pot.

Fig. 4, is a plan view of the ink pot.

Fig. 5, is a side sectional view of the ink pot, disclosing the air chamber and port.

30 Fig. 6, is a cross sectional view of the blotting-inkstand disclosing the blotter axles.

Fig. 7, is a plan view of the housing blank.

35 Fig. 8, is a perspective of the blotter movable side-brace.

Fig. 9, is a perspective of the curtain door.

Fig. 10, is a perspective of the ink pot seat.

Fig. 11, is a perspective of the handle box.

40 Similar letters refer to similar parts throughout the several views.

The general framework of my invention is a shell blank 1, formed of a blank of flexible material so cut that by bending the 45 same, into the form of a semi-ellipse as shown in Fig. 1, in which, when so bent room is made for suspending a blotter roll crosswise within each end, and for centrally suspending an inkstand also crosswise there- 50 in between them.

On one of the edges of the shell blank 1, spaced centrally from its end is provided a narrow protuberating flap 30, capable of being bent to a parallel alignment with the 55 remainder of said edge, for the purpose of

providing a rim roll by which to secure brace means, capable of holding the blank 1, in semi-elliptic form, when it is so bent that its ends touch as shown in Fig. 1.

The shell blank 1, is also provided centrally spaced from its ends, but on the edge adjacent to flap 30 with a dip hole 26 creating an entrance to the funnel 2^c of the inkstand.

Between the dip hole 26 and side flap 30 is 65 also provided a small perforation 34 for the purpose of securing the sliding circular cover 1^a of the dip hole 26 by rivet means 1^b, to shell blank 1.

Shell blank 1 is centrally provided adjacent to dip hole 26, with four oblong slots 25, for the purpose of furnishing means for the attachment of handle box 8, by the insertion of the turn down nibs 14 provided on the bottom of handle-walls 8^a, and 8^b. 70

Spaced from each end in shell blank 1 is provided transverse serrated perforations 31 for the outward and inward passage of the blotter tape 19 when being manipulated upon the spools 7, suspended crosswise within the ends of blank 1, when the same is formed into a box as shown in Fig. 1, permitting the tape 19 to pass under the bottom 18 of said box 1, when rolled from spool 7 to spool 7 by the turning of shafts 7^a, by 85 means of buttons 7^c provided on the ends thereof.

Spaced from each end of shell blank 1, and directioned inwardly are provided tongues 4 formed by perforating the shell 90 blank 1, which tongues are for the purpose of forming base guards within the shell blank 1, when folded, for retaining the inkstand 2 in position.

Spaced near each end of shell blank 1, 95 and to the side of the center thereof is provided a perforation 29 for connectedly securing to the bottom of shell blank 1, by rivet means 3^a of an inkstand seat 3, through perforations 3^c in the continuation 3^b of such 100 inkstand seat 3.

Spaced from each end of shell blank 1, and on the same side thereof as flap 30, is provided protuberating ears 32, having a pair of alinged parallelly disposed oblong 105 perforations 33 in each ear, for the purpose of introducing the nibs 6^a of side braces 6, in securing braces 6 to shell blank 1, in securing the shell blank 1 in semi-elliptical form.

- Shell blank 1 on the same side thereof as flap 30, is provided with oblong parallelly disposed perforations 28 spaced in close proximity to its ends for the purpose of receiving the nibs 5^a or door 5 where the same is secured connectedly to the bottom of shell blank 1, when shell blank 1 is formed into an ellipse by uniting its ends 1^c and 1^d.
- Spaced near each end and aligned with the sides of shell blank 1, and on the same side thereof as strips 20 and 21, is provided in alignment a plurality of parallelly disposed oblong slots 27, the ones nearest each end being for the purpose of engaging the nibs 22^a of brace strip 21 and the others being for the purpose of engaging the ends of strips 20 after shell blank 1 is bent into an ellipse, its ends 1^c and 1^d touching each other, when said ends of strips 20 and nibs 21 are inserted in said slots 27 and turned down forming an eye 13, as disclosed in Fig. 6, the purpose of turning said ends down to an eye 13, being to secure the shell blank 1 in its semi-elliptical form.
- Curtain door 5 provided on the side opposite said strips 20 and 21 is secured to the bottom thereof by eye turns 5^a when inserted in slots 28 and when desired is latched and held in place at its top, by clamp means 5^e cut from its sides 5^b passing and turned upward, and its end 5^c turned flangedly downward, said flanged portions being provided with a tongue 5^d formed by bifurcating the flanged end 5^c, the tongue portion 5^d being turned downward to an alignment with clamp means 5^e thus forming a clasp which engages the enlarged edge of blank 1, formed by crimping flap 30, to an alignment with the edge of blank 1, so that when the said curtain door is attached and closed its top rests against the crimped-formed-edge of blank 1, created by the bending of flap 30, as stated.
- Braces 6 each have a perforation 7^d centrally provided in them, corresponding to perforations 24 provided in braces 20, which perforations 7^d and 24 are provided for the insertion of the shafts 7^a which constitute the support of the blotter clamps 7 in either end of the elliptical box 1, which blotter clamps 7 are so positioned for the purpose of permitting the blotting paper 19 to be mounted thereon in a roll, and to leave and enter through serrated slots 31 in being shifted under the bottom of blank 1, when worn out, or when being attached.
- Blotter shaft 7^a is formed by having each of its ends squared at a point where the same passes through perforations 7^d and 24 in braces 6 and 20, to conform to the squared extensions of holes 7^d and 24. Perforations 7^d of brace 6 and 24 of brace 20, are formed by having the parallel side of the hole 7^d squared and the lateral side of the hole 7^d rounded unto an offset to form a release of

tension and a catch in operating blotter clamp 7 by the manipulation of shaft 7^a suitably therein, as desired, the change in hole 24 not shown.

Blotter clamp 7 is the ordinary roller secured upon a shaft 7^a and is provided with a parallelly disposed groove 7^b spaced midway between its ends, the shafts 7^a being provided at one of their ends with knobs 7^c, for adjusting and turning the same as desired, the ends of the shafts being squared so that when wound sufficiently they may be dropped into the square sides of holes 7^d thus holding the blotter securely in place, thus preventing the roller from turning until raised into the round part of holes 7^d and 24, as desired, while the blotter is extended and moved through serrated perforations 31, from roll to roll as desired.

Beneath the joined ends of the semi-elliptical form 1, and extending between serrated perforations 31, is provided a pad 18, secured to the bottom of form 1, by any suitable means, over which blotter 19 moves, thus providing a cushion bottom for the device, as shown in Fig. 6.

Braces 6 are secured at the bottom to the semi-elliptical box 1, by nibs 6^a turned therein, and are secured to the top of box 1, by means of a clasp formed in the upper end of brace 6, by making an oblong tongue-like incision 6^e therein spaced from the end of brace 6, downwardly disposed, leaving the upward end of the incised portion 6^e attached to brace 6, and turning the incised portion 6^e upward into a tongue in such manner as to press against the edge of the semi-elliptical box 1, the extreme upper end of said brace 6, being flanged at 6^c, the flange 6^c being bifurcated leaving a tongue portion 6^d attached at its inward end and also thus leaving the flanged bifurcated portions 6^c, protuberating into nibs 6^a which latter nibs 6^a being thus flanged and in forming a clasp and with tongue portions 6^d and 6^e do form a clasp, and operate to pinchingly engage the edge of the semi-elliptical box 1 at a point where the ends of flap 30 is crimped to it.

Inkstand base 3 is an oblong strip of suitable material having an angulate offset 3^a bent therein, near its terminal continuation 3^b, the latter containing two perforations 3^c transversely arranged for securing the same to the semi-elliptical box 1, through holes 29 in blank 1, by rivet means 3^d.

When the semi-elliptical box 1 is formed by uniting ends 1^c and 1^d as above described, and tongue guards 4, are bent to vertical position and inkstand seat 3 is secured thereto by riveting the same to the bottom of said elliptical box 1, it will be found that the inkstand base 3 extends between the tongue guards 4, and a similar tongue guard 23 having been formed in brace 21, and bent

115

125

30

abruptly inward, it will be found that the inkstand 2 hereinafter described will fit in upon and rest securely upon the same.

The inkstand 2 is of a length corresponding to the width of blank 1, and when blank 1 is formed into a semi-ellipse as shown in Fig. 1, door 5 is opened by unlatching the same at 5^d and turning the same outward and downward, when inkstand 2 is inserted 10 with part 2 upon seat 3, snugly against brace 21, to which, base 3 is secured by means of a tongue-base 23^a formed tongue end downward in brace 21 by turning upward and inward an oblong tongue shaped slit 23^a 15 stamped in said brace 21, its top end being left attached to the body of said brace 21, the said tongue base 23^a forming a base support upon which the end of inkstand base 3 rests.

20 Above base support 23^a in said brace 21 is provided another tongue shaped brace 23, formed tongue-end downward, which is bent inwardly with an abrupt downward offset, intended to rest against the end of inkstand 25 2 for the purpose of holding it snugly within the semi-elliptical box 1.

Inkstand 2 is formed of a tank having a dip end 17 and a filling end 2^d, its filling end consisting of an oblong chamber 2^d having 30 an ordinary air tight screw top cap, neck and opening 2^b, the dip end consisting of a spoon bowl like portion 17, and having provided in its upper rim portion, connectedly with filling end 2^d, screw thread means 17^a 35 into which is inserted and outwardly secured by screw thread means 15^a a dip basket 15.

Dip basket 15 is provided at the side opposite the filling end with a port 16, below the bottom level of filling end 2^d, through 40 which ink is allowed to pass from the filling end into the dip basket 15. The dip basket 15 is also provided with an ordinary screw top containing a funnel 2^c held in place by the circular top 2^a of a dip basket 15. Dip 45 basket 15 is also provided at its top with an ordinary flat cover 1^a, which flat cover is secured to the top 2^a of dip basket 15 by rivet means 1^b inserted through said cover, to prevent dust and insects from falling therein, and to protect the ink from evaporation.

50 Handle box 8 is formed by stamping and bending any pliable material into an ornamental box form in such manner as to make a handle presenting four sides corresponding to 8^a and 8^b, two of the sides having protuberating parallel aligned lugs 8^d on their bottom edges, capable of being inserted into corresponding holes 25 in the top of the semi-elliptical shell 1, and turned down into 55 clamps, thus securing the handle 8 to the shell 1. On the top of handle 8, is also provided a cover 9 of ornamental design, secured at one of its sides to one of the sides of handle 8 by protuberating lugs turned 60 into eyes 11, inserted in oblong slots 8^c, and

the other side of the lid, is turned flangedly downward to form a clasp in such manner as to snap snugly over the top edge of side 8^b of handle 8. It will be observed, that in this manner the top of shell 1 forms a bottom, which together with sides 8^a and 8^b, and the corresponding front and back, with the top 9 is formed a box 8, capable of holding pens or other materials, at the same time serving as an ornamental handle for the 75 article.

It will be observed that the distinctive feature of inkstand 2 is the fact that the ink is kept in an air tight reservoir 2^a, and is allowed to escape only by use through port 16, 80 provided in the suspended dip basket 15, and thus the ink is kept effectually unexposed to evaporation and dust. It will also be observed that by suspending the dip basket 15, in the end 17 of inkstand 2, by the 85 screw means at top 17^a, with the inside curvatures 2^b of the shoulders of top 2^a, the ink is prevented from spilling through the bell opening 2^c in case of use or overturning, a thing which is not accomplished in other 90 inkstands.

It will also be observed that door 5 and brace 21 are longer than braces 6 and braces 20, that protuberating ears, 32, are longer at their sides nearest the ends 1^d and 1^c of 95 blank 1, also that when flap 30 is bent inward to and upon the main portion of blank 1, it with the attachment of the handle box 8 in holes 25, causes the top of the semi-elliptic box 1, to be flat, the effect further being 100 in attaching the ends 1^c and 1^d to cause the bottom of the device to be longitudinally semi-elliptical in form, so that the device may be rocked back and forth applying its surface thereby to the surfaces upon which 105 it is used the bottom at the same time presenting a flat surface latitudinally.

I claim:

1. In an inkstand housing formed into a semi-ellipse, having therein means for holding an inkstand and center side brace means for supporting the end of an inkstand base, an inkstand base having an angulate offset portion, a short perforated continuation, means for securing the inkstand base at one 110 end to the floor of the inkstand housing, other means for supporting the inkstand base at its other end unto said center side brace of the inkstand housing.

2. In a semi-elliptical blotting inkstand 115 housing having vertical sides, and side braces, a side brace having nib means at one end, its other end being incised and bifurcated the incised and bifurcated portions having in them tongue portions turned in 120 such manner as to operate conjunctively with the flanged portions of the ends of said braces in forming a clasp.

3. In an inkstand housing a door having 125 parallel protuberating nibs capable of be- 130

ing turned into eyes, at one end, its other end having on either side spaced from its end, directioned toward its middle, rectangular incisions for the ends of the incised 5 portions to be bent curvedly upward from such incisions forming the lower jaw of a clasp; a portion of the end of such door flanged right-angularly, the flanged portion of the door bifurcated, leaving the incised 10 section inwardly attached to the flange; the inwardly attached section of the bifurcated end of the door being curvedly bent so as to form the upper jaw of a clasp; bifurcated right-angularly bent nibs on the upper end 15 of said door, directioned with said jaws operating with said jaws and to form a clasp, the whole operating to form a door having fastening means, at its ends.

4. In an inkstand housing a brace having 20 parallel protuberating nibs capable of being turned into eyes at one end, its other end being offset flangedly below the offset of the flanged end of a brace an oblong incision in said brace formed in such way as to leave 25 within the incision a tongue member directioned toward the middle of the brace, the tongue member having a free end, its other end attached to said brace, the length of the tongue member such that when bent 30 curvedly upward, its end conjoins with the flange bent at the end of the brace, forming a clasp, the whole operating to form a brace having fastening means at its ends.

5. In an inkstand housing a pair of braces 35 laterally disposed in upright position at the sides, spaced in suitable proximity from each end and secured to the housing in such manner as to make the housing semi-elliptical in form; a pair of braces having appo-

sitely disposed holes correspondingly formed 40 in their centers, said holes consisting of a rounded portion connected with a square offset from one-quarter of their radius; square shaft members mounted in the holes of the braces of the inkstand housing, button means on the ends of said shafts, spool members provided upon the square shaft members, grooves suitable for inserting the ends of a blotter roll, provided in the surfaces of the spool members; a plurality of 45 serrated groove means right-angularly disposed, parallel with said spools provided in the floor of the housing, suitable to admit the passage of blotter tape from one spool to the other, pad means disposed between the 50 blotter tape and the floor of the housing between the serrated incisions, all for the purposes specified.

6. In a blotting inkstand having a housing, a box handle mounted upon its top and 60 secured thereto by clamp means formed of nibs provided in the edges of the walls of the handle, connected with hole means provided in the top of the housing; the box handle having a lid secured thereto by eye 65 means formed of nibs provided at one side and held in place by hasp means provided by a flange offset provided in the said lid, engaging the edge of the box at the other side, the whole capable of being used as a 70 handle and at the same time forming a pen box, all for the purposes specified.

Signed at Davenport, Iowa, this 20th day of July, A. D. 1920.
